US00D759207S

(12) **United States Design Patent**
Gilbert et al.

(10) **Patent No.:** US D759,207 S
(45) **Date of Patent:** ** Jun. 14, 2016

(54) **FAUCET HANDLE**

(71) Applicant: **Moen Incorporated**, North Olmsted, OH (US)

(72) Inventors: **Christopher Jon Gilbert**, Moreland Hills, OH (US); **Jennifer P. Sedwick**, Lakewood, OH (US)

(73) Assignee: **Moen Incorporated**, North Olmsted, OH (US)

(**) Term: **14 Years**

(21) Appl. No.: **29/510,600**

(22) Filed: **Dec. 1, 2014**

(51) **LOC (10) Cl.** 23-01

(52) **U.S. Cl.** USPC **D23/252**

Primary Examiner — Robert Delehanty

(74) *Attorney, Agent, or Firm* — Calfee, Halter & Griswold LLP

(57) **CLAIM**

The ornamental design for a faucet handle, as shown and described.

DESCRIPTION

FIG. 1 is a perspective view of a faucet handle of the new design;

FIG. 2 is a front elevational view of the faucet handle of FIG. 1, the rear elevational view being a mirror image thereof;

FIG. 3 is a left side elevational view of the faucet handle of FIG. 1;

FIG. 4 is a right side elevational view of the faucet handle of FIG. 1;

FIG. 5 is a top plan view of the faucet handle of FIG. 1; and,

FIG. 6 is a bottom plan view of the faucet handle of FIG. 1.

The portions of the Figures shown in broken lines are not part of the claimed design and are for illustration only.

1 Claim, 3 Drawing Sheets
